Term of patent 14 years

(Cl. D52—2)

Fig. 1.

Fig. 2.

Fig. 6.

FIG. 1 is a front elevational view of a gasoline dispenser showing one embodiment of our new design;

FIG. 2 is a side elevational view thereof with the opposite side being substantially the same in appearance;

FIG. 3 is a front elevational view of another embodiment of our new design, one side of which is the same as FIG. 2 and the other side of which is substantially the same in appearance as FIG. 2 but without the fittings;

FIG. 4 is a front elevational view of still another embodiment of our new design;

FIG. 5 is a side elevational view of one side of the embodiment shown in FIG. 4 with the opposite side being substantially the same in appearance but without the fittings; and

FIG. 6 is a side elevational view of a further embodiment of our new design having the same appearance in

front elevation as FIG. 1, and the opposite side of which is substantially the same in appearance.

The rear views in elevation of all of the described embodiments are identical with the illustrated front views in elevation.

We claim:

The ornamental design for a gasoline dispenser, as shown and described.
